E. WAHLSTRÖM

REFINER FOR WOOD PULP

Filed May 16, 1917

Inventor
Einar Wahlström
By Hannorff Atty

UNITED STATES PATENT OFFICE.

EINAR WAHLSTRÖM, OF VITTINGFOS, NORWAY, ASSIGNOR TO A/S. MYRENS VERKSTED, OF CHRISTIANIA, NORWAY.

REFINER FOR WOOD PULP.

Application filed May 16, 1917. Serial No. 169,040.

(GRANTED UNDER THE PROVISIONS OF THE ACT OF MARCH 3, 1921, 41 STAT. L., 1313.)

To all whom it may concern:

Be it known that I, EINAR WAHLSTRÖM, a subject of the King of Norway, residing at Vittingfos, in the Kingdom of Norway, have invented certain new and useful Improvements in Refiners for Wood Pulp (for which I have filed an application in Norway May 9, 1916, Patent No. 27,544); and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The present invention relates to refiners for wood pulp and has for its object a particular arrangement for mounting the bed stone or stones.

The invention may be applied on refiners with vertical as well as horizontal axis but is particularly adapted for refiners of the last named type.

In order to avoid the vibrations easily produced with stones supported in the ordinary way by screws, which vibrations act to lessen the efficiency and cause uneven grinding, and in order to at the same time always keep the charging chamber automatically open, the bed stone or stones according to the present invention are mounted on a pivot located on the inlet side, so that the edge of the bed stone at the inlet lies outside the connecting line between the axis of the refining stone and the pivot of the bed stone.

On the drawing is shown a diagrammatical section through a form of the invention as applied on a refiner with horizontal axis, the bedding of which consists of two stones, one over and one below the rotating grinding stone.

The bed stones A are placed in frames

B supported on one side by trunnions C 45 and on the opposite side in the usual manner by screws D. E are the inlets and F the outlets for the pulp. The bearings for the trunnions C should be vertically adjustable so that they may be adjusted in accordance with the wear of the stones. 50

In refiners constructed in this way the rotating stone will exert a pull on the bed stone in the direction from its trunnions, the screws for the adjustment will therefore not be exposed to lateral stress and vibrations as is the case in refiners the bed stones of which are supported with four screws. The increasing pressure between the stones towards the outlet and the fact that the inlet 60 space is widened by tightening the screws, combine to increase the efficiency of this refiner.

I claim:

1. In refiners for wood pulp a bed stone 65 pivotally supported near the pulp inlet in such a manner, that the inlet edge of the bed stone is removed from the grinding surface when the opposite side of the bed stone is moved towards the grinding surface whereby the inlet space is automatically kept open, while the pressure is steadily increased towards the outlet. 70

2. A refiner for wood pulp comprising a rotary grinding member and a cooperating 75 bed member mounted in pivoted relation to the rotary member, said cooperating member having its inlet edge in front of a plane extending through the axis of the rotary member and the pivotal axis of the bed 80 member.

In testimony that I claim the foregoing as my invention, I have signed my name in presence of two subscribing witnesses.

EINAR WAHLSTRÖM.
